UNITED STATES PATENT OFFICE.

LEONARD AITKEN, OF LAWRENCE, MASSACHUSETTS.

WEFT-REPLENISHING LOOM.

1,307,994.

Specification of Letters Patent. Patented June 24, 1919.

Application filed May 22, 1914. Serial No. 840,239.

To all whom it may concern:

Be it known that I, LEONARD AITKEN, a citizen of the United States, and resident of Lawrence, in the county of Essex and State 5 of Massachusetts, have invented certain new and useful Improvements in Weft-Replenishing Looms, of which the following is a specification.

The purpose of the present invention is to 10 provide improved driving mechanism for a weft-replenishing loom in which the weaving mechanism and weft-replenishing mechanism are operated alternately. The driving mechanisms hitherto used for looms of 15 this kind are not capable of transmitting sufficient power when operating on the heavier grades of fabric, such as heavy duck, and the driving mechanism shown by the accompanying drawings and hereinafter described and claimed is designed and arranged 20 to drive looms for the production of both the lighter and heavier fabrics without slip of the friction driving elements.

Many weft-replenishing looms now in use 25 have a shuttle-carrier for carrying the filled shuttles one by one from a shuttle magazine to the change shuttle-box of the weaving mechanism, such carrier being operated by a "change-shaft" while the weaving mechanism is at rest temporarily. It happens 30 too frequently in such looms that the shuttles drop from their carrier in transit, or if they do not drop they become disarranged on the carrier, with the result that they fail 35 to take the necessary position in the shuttle-box. This is caused partly by jerking action of the carrier, and partly by tipping of the shuttle-supporting surface as the carrier travels in an arc about a horizontal axis.

40 I use a shuttle-carrier and change-shaft to interchange the spent shuttle and a spare filled shuttle, but, in order to avoid the dropping and disarranging above mentioned, I provide improved transmission mechanism 45 that drives the change shaft so smoothly and evenly that the jerking action of the carrier is eliminated. I have found in practice that the jerking of the change shaft in these looms, as hitherto made, is due partly to 50 looseness of the inclined transmission shaft in its bearings, and that such looseness is due to inability to keep the shaft suitably lubricated. The jerking is also due partly to running the transmission shaft at a speed much 55 faster than that of the crankshaft that op-

erates the lay. The excessive speed of the transmission shaft, compounded with the inability to keep it lubricated, ruins the bearings in a very short time. Hence the change shaft and its cams have an uneven rate of 60 speed. But, although this is bad in itself, its jerking effect upon the shuttle-carrier is increased in amplitude about threefold by the arrangement of the lever that acts as a 65 part of the shuttle-carrier.

My improved transmission mechanism eliminates the jerking of the shuttle-carrier by a new arrangement of gearing whereby the difficulties that have hitherto originated in the inclined transmission shaft are eliminated. In conjunction with the gearing 70 above mentioned I have introduced gearing that enables the loom to weave the heavier grades of fabric without slipping of the power belt.

75 Of the accompanying drawings, which illustrate one form in which the invention may be embodied:

Figure 1 represents an end elevation of the 80 drive end of a weft-replenishing loom, the controlling elements of which are adjusted to disconnect the power.

Fig. 2 represents a top plan view of the mechanism included in Fig. 1.

Fig. 3 represents a sectional view of the 85 structure intersected by line 3—3 of Fig. 6.

Fig. 4 represents a horizontal section of the clutch mechanism which drives the weft-replenishing mechanism.

Fig. 5 represents a section through the 90 structure intersected by line 5—5 of Fig. 4.

Fig. 6 represents a front elevation, partly in section, of the structure shown by Fig. 4.

The same reference characters indicate the 95 same parts wherever they occur.

In looms of the type hereinbefore mentioned the main pulley is loosely mounted on the crankshaft that reciprocates the lay, and a friction clutch is arranged to transmit rotation directly from said pulley to the crank-shaft. There is no speed reduction between the pulley and the crankshaft. One difficulty due to such arrangement of the clutch is that it slips when the loom is used for weaving the heavier fabrics, and another 100 difficulty is that the fly-wheel effect of the pulley is not sufficient for the requirements of the weft-replenishing mechanism. It is a fact, recognized by all builders and users of weft-replenishing looms, that the weft- 105

110

replenishing mechanism requires the utmost delicacy and accuracy of action, although the mechanism for such purpose is, of necessity, crude in comparison to the average machine used in other arts. According to my present invention the driving mechanism for weaving, and that for operating the so called "change shaft", are reorganized and slightly amplified (back-gearing being added), with the result that the capacity for weaving the heavier fabrics is increased and the weft-replenishing mechanism is caused to operate without the jerking motions that have, hitherto, caused miscarriage and dropping of the shuttles.

In my present application I use a friction clutch of the same type and size as heretofore, but instead of arranging this clutch upon the crankshaft I arrange it upon a countershaft and connect it with the crankshaft by gearing which gives the friction clutch the advantage of leverage. This arrangement enables the friction clutch to overcome greater mechanical resistance; and in order to maintain the desired running speed of the loom I increase the angular velocity of the pulley sufficiently to offset the speed loss due to the reduction gearing. In addition to making the loom capable of weaving heavier fabrics, this new arrangement causes the weft-replenishing mechanism in particular to operate more smoothly, the pulley acting as a flywheel and rotating at greater angular velocity than hitherto. According to the proportions which I have illustrated, the angular velocity of the pulley is twice as great as that of the crankshaft; but this ratio may be varied according to conditions.

In the looms of the type above mentioned the weft-replenishing mechanism includes a cam shaft, commonly termed the "change shaft", and a clutch for driving the same. Suitable clutch-controlling mechanism is provided for causing the cam-shaft clutch to remain disconnected so long as the main clutch is connected, and vice versa, to the end that the weft-replenishing mechanism can operate only when the weaving mechanism is at rest, and the weaving mechanism can operate only when the weft-replenishing mechanism is at rest. The driving element of the cam-shaft clutch is, however, continuously driven through a transmission shaft. This shaft, rotating continuously, makes twice as many revolutions as the crankshaft, in looms as hitherto made, although it is called into service only about one per cent. of the time during which the loom is working. Its excessive rotation and wear in its bearings cause it to become loose prematurely, and the jerking due to such looseness and the consequent imperfect meshing of the gears affect the shuttle carrier so that the shuttles are too frequently

dropped. This increases the idle period of the loom, and calls for an attendant to restore the loom to running condition.

My present invention reduces the speed of the transmission shaft to about one-sixth of the speed of the crankshaft, notwithstanding the doubled speed of the driving pulley, and thus eliminates the aforesaid cause of dropping the shuttles from the shuttle carrier. The transmission shaft is driven by the pulley independently of the friction clutch that drives the weaving mechanism. I also employ a clutch for driving the cam shaft of the weft-replenishing mechanism, and the driving member thereof is continuously driven by the transmission shaft.

Referring to the accompanying drawings,—one of the two main frame members of the loom is indicated at 10, and the crank-shaft which reciprocates the lay is indicated at 11. A gear 12 affixed to the crankshaft meshes with a gear 13 affixed to a countershaft 14. In the present instance the diameter of the gear 12 is twice as great as that of the gear 13; but this ratio may be varied and still be within the scope of the present invention provided the gearing is such as to make the angular velocity of the crankshaft less than that of the countershaft. 15 indicates the driven element of a friction clutch, and 16 indicates the driving element. A layer 17 of suitable friction material such as leather is interposed between members 15 and 16. The member 16 in the present instance is a pulley and is intended to be driven by a belt 18. The pulley is loosely mounted upon the shaft 14 and the driving engagement as between the clutch members is effected by pressing the member 16 axially toward the member 15. When such pressure is relieved the clutch members are free from each other. The clutch operating mechanism includes a collar 19 and a shipper 20. The collar is loosely mounted upon the hub of the pulley 16 and is arranged to press axially against a shoulder 16' of said hub, for the purpose of setting the clutch. Radial studs 21 affixed to the collar engage the shipper 20, which is forked at 22 for this purpose. The shipper 20 is in the form of a lever and its fulcrum is indicated at 23. A rod 24 connects the shipper with a lever 25 whose fulcrum is indicated at 26. A link 27 connects the lever 25 with a manually operative lever 28 which has a handle 29. This lever is affixed to a rockshaft 30 which extends throughout substantially the entire width of the loom and which is arranged under the breastbeam (not shown). When the handle 29 is moved forwardly, or to the left with reference to Fig. 1, it moves the clutch member 16 toward the clutch member 15 to effect driving connection. The pivot stud 31 which connects the link 27 and lever 28 is arranged to cross the

line which intersects the axis of rockshaft 30 and the axis of stud 32 which connects the link 27 with lever 25, the connection in this respect being a form of toggle which is adapted to lock itself in driving position when the stud 31 has crossed the aforesaid line. A stop 33 limits the forward movement of the lever 28.

Although the lever 28 is intended to be 10 operated manually under certain conditions, it is also intended to be operated mechanically in accordance with well-known practice, to set the main clutch for driving the weaving mechanism upon the completion of 15 each weft-replenishing operation.

The cam shaft 40 for the purposes of the present invention is a sufficient representation of the weft-replenishing mechanism. My present invention does not deal with 20 any specific form or details of weft-replenishing mechanism, but deals rather with the driving mechanism therefor and the driving mechanism which drives the weaving mechanism.

25 The clutch that controls and drives the weft-replenishing mechanism is shown best by Figs. 4, 5 and 6, and its location relatively to other parts of the loom is shown by Fig. 2. A sleeve 41 is loosely mounted upon the cam shaft. This sleeve is provided with a disk 42 which acts as the driving member of the cam-shaft clutch. This disk has formed in it a circular series of holes 43—as many as may be desired, provided sufficient stock is 30 left between them to sustain the load. The driven element of this clutch comprises a disk 44 and a dog 45 movably mounted thereon. The dog is formed upon a lever 46 which has an opening occupied by the hub 47 of 35 the disk. A pivot pin 48 connects the lever and hub. The dog 45 is arranged to occupy any one of the holes 43 with which it may register. A tailpiece 49 formed upon the lever 46 coacts with suitable controlling 40 means, hereinafter described, to withdraw the dog 45 from the disk 42. When the tailpiece 49 is released, as will be understood after further description, the dog 45 is moved to one of the holes 43 in consequence 45 of the action of the spring 50, said spring being carried by the disk 44. The disk is provided with a notch the sides of which are arranged to engage the dog 45 to brace the same when the clutch is connected.

50 The sleeve 41 carries a bevel gear 51 which is driven by a bevel gear 52. Gear 52 is affixed to a shaft 53. A spiral gear 54 affixed to shaft 53 is driven at comparatively slow speed by a continuously driven worm 55 affixed to the hub of the pulley 16.

55 Suitable transmission means capable of slipping is interposed between the bevel gear 51 and the sleeve 41, as a safeguard to prevent damage to any of the parts in case the 60 operation of the weft-replenishing mecha-

nism is prevented by any irregularity such as the disarrangement of a shuttle. The gear 51 is rotatable with relation to the sleeve 41 when the rotation of the sleeve is prevented as above suggested. The sleeve is 70

provided with a disk 56, and a layer 57 of suitable friction material is interposed between this disk and the back of the gear. The gear is held against the layer 57 by a plurality of keepers 58, each of which has 75 a head 59. The gear is formed with continuous circular grooves 60 of T-shaped cross section. The heads 59 of the keepers are arranged in said grooves, and the shanks of the keepers extend through the layer 57 80 and through the disk 56 and are provided with nuts 61. Each keeper has a helical compression spring 62 whereby the gear 51 is held in driving engagement with the friction material 57. The degree of pressure as 85 between the gear 51 and friction material 57 may be varied by adjusting the nuts 61 and springs 62.

The mechanism for controlling the weft-replenishing mechanism is designed to permit the cam shaft 40 to make one revolution and then disconnect the clutch which drives said shaft. For this purpose a knock-off device 63 is provided, this device being arranged to coact with the tailpiece 49 of the 90 clutch lever 46. The knock-off is arranged upon a pivot stud 64, said pivot stud being shown by Fig. 6 as being supported by a bracket 65, the bracket being shown as being affixed to the frame member 10. One 95 end of a link 66 is pivotally connected at 67 to the knock-off device, and the other end of said link is connected to the lower end of a rod 68. This rod extends loosely through the free end of an arm 69 (Figs. 1 and 2). 100 This arm is affixed to a rockshaft 70. A head or collar 71 affixed to the rod 68 is arranged to be engaged and lifted by the free end of the arm 69. The rockshaft 70 is intended to be operated by well-known feeler 105 mechanism which is arranged to project into the shuttle when the lay is forward, to engage the filling which remains upon the bobbin in the shuttle. I have not attempted to illustrate the feeler mechanism other than to 110 include in Fig. 1 the lever 72 by which the rockshaft 70 is actuated when the filling on the bobbin is exhausted to a predetermined degree. As my present invention does not deal specially with the feeler mechanism, it 115 will be sufficient for present purposes to state that the rockshaft 70 remains stationary throughout the weaving operation until the filling on the bobbin is so nearly exhausted as to require new filling, and that when the 120 filling reaches this predetermined state of exhaustion the upper end of lever 72 is moved forward to lift the rod 68. This movement is transmitted to the link 66.

125 Referring to Fig. 6, it will be seen that the 130

link 66 is provided with a shoulder 73 and that this shoulder is caught on an abutment 74. The effect of lifting the rod 68 as described is to disengage the shoulder 73 from the abutment 74, thus releasing the tailpiece 49 so that the dog 45 may be moved into one of the holes 43 by the spring 50. As the disk 42 is driven continuously, the cam shaft 40 will begin to rotate as soon as the dog 45 has entered one of the holes 43. The setting of the clutch for driving the weft-replenishing mechanism is attended by the releasing of the clutch which drives the weaving mechanism, the actuation of the rock-shaft 70 in consequence of filling exhaustion causing movement of the starting lever 28 to the rear, through suitable connections well known but not shown.

I claim:

20 1. In a weft-replenishing loom, in combination, weaving mechanism and weft-replenishing mechanism arranged to operate alternately, said weft-replenishing mechanism including a weft-replenishing shaft, a transmission shaft, a continuously driven pulley, speed-reducing gearing arranged to transmit rotation from said pulley to said transmission shaft, and means arranged to transmit rotation from said transmission shaft to said weft-replenishing shaft.

25 2. In a weft-replenishing loom, in combination, a crankshaft for reciprocating the lay, a driving pulley, means, including a friction clutch and speed-reducing gears, arranged to transmit rotation from said pulley to said crankshaft, a weft-replenishing shaft, a transmission shaft, gearing arranged to transmit rotation from said transmission shaft to said weft-replenishing shaft, and means arranged to 30 transmit rotation from said transmission shaft to said weft-replenishing shaft.

35 3. In a weft-replenishing loom, in combination, a driving pulley, a weft-replenishing shaft, a transmission shaft, a worm arranged to be driven by said pulley, a worm gear affixed to said transmission shaft and arranged to be driven by said worm, whereby the speed of said transmission shaft is re-

duced, and means arranged to transmit rotation from said transmission shaft to said weft-replenishing shaft.

4. In a weft-replenishing loom, in combination, weaving mechanism and weft-replenishing mechanism arranged to operate alternately, a continuously driven pulley, speed-reducing gearing arranged to transmit rotation from said pulley to said weaving mechanism, said weft-replenishing mechanism including a weft-replenishing shaft, a rotatable transmission member, speed-reducing gearing arranged to transmit rotation from said pulley to said transmission member, and means arranged to transmit rotation from said member to said weft-replenishing shaft.

5. In a weft-replenishing loom, in combination, a crankshaft for reciprocating the lay, a driving pulley, means, including a friction clutch and speed-reducing gears, arranged to transmit rotation from said pulley to said crankshaft, a weft-replenishing shaft, a transmission shaft, gearing arranged to transmit rotation from said transmission shaft to said weft-replenishing shaft, and gearing arranged to transmit rotation from said pulley to said transmission shaft, the latter said gearing being arranged to reduce the speed of said transmission shaft to amplify the fly-wheel effect of said pulley upon the latter.

6. In a weft-replenishing loom, in combination, a crankshaft for reciprocating the lay, a pulley, disconnectible means arranged to transmit rotation from said pulley to said crankshaft, a weft-replenishing shaft, a transmission shaft, means arranged to transmit rotation from said transmission shaft to said weft-replenishing shaft, and speed-reducing gearing arranged to transmit rotation from said pulley to said transmission shaft.

In testimony whereof I have affixed my signature, in presence of two witnesses.

LEONARD AITKEN.
